UNITED STATES PATENT OFFICE.

JOSEPH HREN, OF KINGSTON, NEW YORK, AND CARL EISENLOHR, OF NEWARK, NEW JERSEY.

MACHINE FOR MAKING PAPER-BOX BLANKS.

Application filed July 7, 1923. Serial No. 650,024.

To all whom it may concern:

Be it known that we, JOSEPH HREN and CARL EISENLOHR, both citizens of the United States, and residents, respectively, of Kings-
5 ton, in the county of Ulster and State of New York, and Newark, in the county of Essex and State of New Jersey, have invented certain new and useful Improvements in Machines for Making Paper-Box
10 Blanks, of which the following is a specification.

The principal object of this invention is to improve upon the construction of a machine disclosed in our prior Patent No.
15 1,293,782, granted Feb. 11, 1919, which machine is of the type wherein the blanks are constructed of three separable sheets of material which are fed to and secured together by the machine thereby avoiding the waste
20 formerly caused by the manufacture of the blanks out of a single sheet of material.

Considered in its more specific aspects the invention consists in the following further improvements upon the construction
25 of the machine disclosed in said patent. 1. Improvement of the means for feeding the sheets from the sheet-holding means to the presser mechanism. 2. Improvement of the glue applying and feeding structure. 3.
30 The provision of means to automatically stop the actuation of the presser mechanism upon a failure of the feeding means to feed a sheet. 4. The provision of means to automatically stop the actuation of the presser
35 mechanism if more than one sheet is fed at the same time from any one of the sheet magazines. 5. Improvement and simplification of the side and central sheet jogging and registering means. 6. The inclination
40 of the machine to cause the sheets to fall under the influence of gravity from the feeding means between the presser mechanism and bed plates. 7. The improvement of the sheet stopping means. 8. The provision of
45 means to prevent rebounding of the sheets after they engage the sheet stopping means. 9. The provision of means to eject the finished blanks from the machine. 10. The provision of anti-friction means to prevent
50 undue wear upon the pressers and the actuating cams thereof by providing a rolling frictional contact means.

For the accomplishment of these and such further objects as will be apparent to those skilled in the art to which this invention
55 appertains, the invention consists of the following construction, combination and arrangement of parts hereinafter specifically set forth and illustrated in the accompanying drawings forming a part hereof, wherein
60 is shown an illustrative embodiment of our invention, but it will be understood that such changes, variations and modifications may be resorted to as fall within the scope
65 of the claims hereunto appended.

In the drawings:

Fig. 1 is a side view of our improved machine; Fig. 2 is a vertical section on the line 2—2 of Fig. 3; Fig. 3 is a vertical section on the line 3—3 of Fig. 2; Fig. 4 is a horizontal section on the line 4—4 of Fig.
70 2; Fig. 5 is an enlarged detail in side elevation of the center sheet feeding mechanism showing the feed at the beginning of its feeding stroke; Fig. 6 is a view similar to Fig. 5 showing the feeding mechanism at the end of its stroke; Fig. 7 is a horizontal section on the line 7—7 of Fig. 6; 8 is a sectional detail of the glue feeding and applying device; Fig. 9 is a section on the line 80 9—9 of Fig. 8; Fig. 10 is a section on the line 10—10 of Fig. 3 showing the inoperative position of the parts for actuating the sheet stopping means; Fig. 11 is a view similar to Fig. 10 showing the operative 85 position of the parts; Fig. 12 is an enlarged detail of the centre sheet joggers and the means for actuating said joggers; Fig. 13 is a section on the line 13—13 of Fig. 3; Fig. 14 is a section on the line 14—14 of Fig. 4 and Fig. 15 is an enlarged detail of 90 the automatically operated stop clutch.

As shown in the drawings the numeral 20 indicates the main side frames of the machine, the bottom parts of which are extended to form a substantial floor engaging surface and the upper portion 21 of which extends in a rearwardly inclined direction as clearly shown in Figs. 1 and 3. The upper portion 21 of each of the side frames is 100 provided with a rectangular cut out portion 22 to the top of which is secured an auxiliary frame 23 having a forwardly projecting arm 23^a to which is secured a plate

23^b which forms the rear of the centre sheet magazine. Suitably secured to the front of the upper frame portions 21 is a pair of brackets 24 which support the feed magazines and feeding mechanism.

Sheet magazines and feeding mechanism.

A pair of transversely extending supporting rods 25 are secured, as by the knee brackets 25^a, to the upper face of the brackets 23 adjacent the front and rear thereof, and a plurality of sheet supporting rails 26 extend between the supporting rods 25 adjacent the centre thereof to form a supporting surface for the central sheets A. Slidably mounted on the rods 24 are a pair of plates 27 having the nuts 28 secured to their under faces for engaging the screw 29, by means of which the position of the plates 20 may be adjusted. Extending upwardly from and secured to each of the plates 27, a short distance inwardly from its inner edge, is a side plate 30, which defines the sides of the central sheet magazine, the central sheets 25 resting upon the inner edges of the plates 27 and the sheet supporting rails 26.

Adjustably mounted on each plate 27, as by means of the brackets 31, having the elongated slot 32 therein, is an outer side plate 33 which with the side plates 30 and the plates 27 defines the magazine for the side wings B of the tripartite blank, a suitable wing nut 34 being provided to secure the plates 33 in adjusted positions. Each plate 27 is provided with an elongated slot 35 in each of which slots and between the rails 26 a sheet feeding device, indicated generally by the numeral 36, is mounted.

Secured to the under face of each plate 27 adjacent the outer edge thereof is a guide bracket 37, in which are slidably mounted the outer ends of a cross rod 38, provided with a pair of downwardly projecting apertured bosses 39 to which the crank rods 40 are connected. Crank rods 40 are driven by crank discs 40^a secured upon a crank shaft 62 to be presently described. Each feeding device 36 consists of a lower block 41, (see Figs. 5, 6 and 7), secured as by the clamp 42 to cross rod 38 and connected to each block 41, as by the links 43, is an upper block 44 provided at its front end with a plurality of upwardly extending teeth 45 adapted to engage with the sheets to be fed. The rear end of upper block 44 has slidably mounted therein a pair of spring pressed shoes 46 which are adapted, when the feeding device 26 is moved from the position shown in Fig. 5 to the position shown in Fig. 6, to engage with the restricted portions 48 of the slots 35 and a similar restricted portion between the rods 26 and move the upper block 44 from its operative to its inoperative position. When the shoes 46 are in the restricted portions 48 the braking ef-

fect thereof will cause the upper block to move to the position shown in Fig. 5 to cause the teeth 45 to engage with the under face of the sheet and force it outwardly to be engaged by the cooperating feed rolls 49. 70

Driving mechanism.

The driving mechanism consists of a main shaft 50, journalled in suitable bearings in the top of the side frames 20, and provided with a driving pulley 51 adapted to be driven from any suitable source of power. A hand wheel 52 is secured to one end of the main shaft to enable the machine to be driven by hand whenever necessary or de- 75 sirable.

To the opposite end of main shaft is secured a spur pinion 53, meshing with a spur gear 54, upon pressure shaft 55, journalled in bearings 56 which project downwardly from the auxiliary frame-work 23. A sprocket wheel 57 secured to main shaft 50 drives a sprocket chain 58 which is trained about a sprocket 59, secured to the shaft 49^a upon which lower feed rolls 49 are secured, and also about another sprocket 60 secured to a transverse shaft 61. 85

A cam shaft 62 is driven from the pressure shaft 55 by means of suitable sprockets and chain 63. 90

Glue applying device.

Slidably mounted in suitably apertured lugs 64 and 65 projecting rearwardly from the plate is a pair of hollow pipes or tubes 66 having secured to their upper ends the glue pots 67. Each of said tubes is widened at its lower end to form a delivery spout 68 adjacent the mouth of which is rotatably mounted a toothed glue feeding wheel 69, which is rotatably mounted in the elongated grooves 70 provided in the inner walls of the tube, whereby the periphery of feeding wheel 69 will rest by gravity upon and will be driven by contact with a toothed glue applying wheel 71 rotatably mounted upon shaft 49^b upon which the upper feed rolls 49 are secured. A valve 66^a is mounted in each tube for controlling the flow of glue from the glue pots 67 to the delivery spout 68. It will be noted that the tubes 66 with their associated parts rest by gravity upon the wheels 71 thereby causing the wheels 71 not only to prevent the glue from accumulating upon the edges of the spout 68 but also in effect grind a tight joint upon the spout. 110

Sheet transferring and registering mechanism.

A box-like frame structure 75 is resiliently supported upon the lower faces of the cut out portion 22 by means of the springs 76 and extends transversely across between the frame 20, bolts 77 acting to retain the 130

structure 75 in position. Rotatably mounted in suitable bearings 78, secured to the bottom wall of the structure 75, is an adjusting screw 79 upon the outer end of which 5 is secured an operating handle 80. A sprocket chain 81 is trained about suitable sprockets mounted on the shafts 79 and 29 (see Fig. 4.) A pair of brackets 82 each having an upwardly extending bed plate 10 83 are provided with the threaded bosses 84 engaging the screw 79 by means of which the brackets 82 may be adjusted transversely of the machine. Secured to the outer side of each of the plates 83 adjacent the top 15 thereof, is a table 85, in the vertically extending side flanges 85^a of which the transfer rolls 86, (see Figs. 4 and 14) for the side sheets B are rotatably mounted, the front one of said rolls being rotated by the 20 chain 87 from the lower shaft 49^a of lower feed roll 49 and the rotation being transmitted to the remaining transfer rolls by the gearing 88. A co-operating rotatably mounted pressure roll 91 is provided for each of the 25 transfer rolls 86, said pressure rolls being held in yielding engagement with the transfer rolls by springs 92, seated in suitable pockets in a removable frame 93, detachably secured to the table 85 in any suitable manner. A grooved guide rail 94 is secured to the 30 inner face of each flange 85^a and projects forwardly towards the feed rolls 49 to guide the central sheets from the magazines to the pressure mechanism to be hereinafter 35 described. Each table 85 has an upwardly and transversely extending portion 95 provided with a dovetailed guide 95^a in which the pressure 96 to be hereinafter described are slidably mounted. Slidably mounted in 40 suitable bearings in the portion 95 is a rod 97 upon which the side sheet joggers 98 are adjustably secured. A slide 100 which is connected to the rod 97 by means of a bracket 99 is slidably mounted to the under 45 surface of the table by means of a plate 101, said slide being provided with an elongated slot 100^a in which the anti-friction rollers 102 are received. The inner end of each slide has depending therefrom a roller 50 103 which engages within a cam groove 104 in cam 105 secured to cam shaft 62.

The joggers for the central sheet A consist of a lever 106, (see Figs. 2 and 12) 55 pivotally mounted as at 107, upon the portion 95 of table 85, said lever having an upper arm 106^a adapted to be engaged by a button 108 projecting from the outer face of the presser 96, and the lower arm 106^b, of said lever is tapered as at 106^c to guide the side sheets B under the lever. A spring 106^d is provided to normally hold the levers 106 in an inclined position. Slidably mounted upon the inner face of each bed plate 83 60 by means of the bracket 109 is a rail 110, springs 111 (see Fig. 2) being provided to

normally hold the rail in the upper position shown in Fig. 3.

Means are provided for stopping and holding the sheets until the pressers 96 have been actuated and said means comprise 70 the lever 112, one end of which is pivotally mounted upon a shaft 113 secured in bosses 114 depending from the bottom of table 85, a torsion spring 115 being suitably anchored to the shaft and lever to normally hold the lever in elevated position. The other end of lever 112 is extended laterally to form the arm 112^a and is provided with an elongated slot 112^b in which a stop 116 for the central sheet A is adjustably secured. Intermediate its ends the lever 112 is provided with a second laterally extending arm 112^c provided with an elongated slot 112^d in which is secured a stop 117 for the side sheets B. Means are provided for moving the levers 112 upon their pivots to lower the stops 116 and 117 and comprises a trigger 118 (see Figs. 10 and 11) pivotally mounted upon each of the rails 110, one end of said trigger being adapted to engage with a small lug 119 projecting rearwardly from bed plate 83 when the rails are depressed, and the other end of the trigger 118 engages a lever 120 also pivotally mounted upon the rail 111 to cause said lever to be moved from the position shown in Fig. 10 to the position shown in Fig. 11, lever 120 engaging the top of lever 112 to move it downwardly and thus move the stops 116 and 117 to inoperative position.

Each of the top feed rolls 49 is mounted in a swinging frame 49^a which is urged by the spring 49^d to hold the top roll yieldingly towards the bottom roll 49, suitable stops being provided to hold the top roll from contacting with the bottom roll, the top roll only rotating during the passage of a sheet. It will be noted by referring to Fig. 2 that the lower end of plate 23^b terminates a distance from the rod 26 and plates 27 just sufficient to permit the passage of a single sheet.

Presser mechanism.

Secured upon the pressure shaft 55 is a pair of cams 121 (see Figs. 2, 3 and 13) which engage within an opening 122 in the upper end of the pressers 96, suitable collars 123 being provided to prevent movement of the cams longitudinally of the shaft 55. It will be noted that the cams 121 are of sufficient length to permit transverse movement of the pressers when the parts are adjusted for different sized blanks.

Slidably mounted upon the lower face of the opening 122 is a roller cage 124 having the rollers 125 therein, plate 126 being secured to the sides of the pressers to prevent longitudinal movement of the rollers and

to serve as guides for the plates 127, against which the cams 121 engage to force the pressers 96 downwardly. Springs 128 and 129 are provided to normally urge the rollers 125 and plates 127 respectively, to the right in Fig. 13. Pressers 96 are provided with a dovetailed web 96^a, to engage slidably within the dovetailed guide 95^a hereinbefore mentioned, which causes the pressers to be held in alignment with the top face of bed plates 83. Referring to Fig. 2 it will be noted that the pressers spread outwardly longitudinally of the machine toward the bottom edges and that the front lower edges of the pressers are flared upwardly as at 129 to allow the central sheets to readily pass beneath the pressers.

Rebound preventing device.

Pivotedly connected to the rear wall of the structure 75 as by bracket 130 (see Fig. 2) is a lever 131 which extends forwardly under cam shaft 62 centrally of the pressers 96 and is provided at its forward end with the yoke arms 132 between which is rotatably mounted a roller 133, which is driven from shaft 61 by means of a belt 134. Suspended above and in line with roller 133 for free vertical movement is a roller 135 rotatably mounted in one end of a rod 136, the other end of which is pivoted to the arm 23^a of bracket 23. Lever 131 has mounted thereon a wear plate 137 immediately below the cam shaft 62, with which a cam 138 secured to said shaft is adapted to engage and force the lever downwardly at predetermined intervals, while the yoke arms 132 on the forward end of the lever are provided with the notches 139 in which the rounded end of a pivotally mounted counterweighted lever 140 is engaged to normally hold the lever 131 with roller 133 in its upper position.

Rail depressing mechanism.

While the pressers 96 would be sufficient to press the rails 110 downwardly against the action of springs 111 to bring the edges of the central sheet into contact with the glued edges of the side sheets, we have found it preferable, in order to permit the finished blank to be readily ejected, to provide means for holding the rails 110 in lowered position after the pressing operation is completed and for this purpose the upper end of a link 141 (see Figs. 10 and 11) is pivotally connected substantially to the centre of each rail. The lower end of each link 141 has secured thereto the upper end of a curved rod 142, the lower end of which is pivotally secured as at 143 to the bed plate 83. A cam 144 is secured upon cam shaft 62 in alignment with each rod 142 to engage therewith and hold the rails downwardly after the

pressers 96 have started their upward movement.

Blank ejecting means.

Secured upon the shaft 61 at the center 70 of the machine is a roller 145 (see Fig. 2) the periphery of which is spaced below the lower face of central blank A when the rails are in their upper position, but which is adapted to engage with the blank when 75 the rails 110 are depressed. A roller 146 is mounted above the roller 145 upon a lever 147 secured upon a shaft 148 rotatably supported in a bracket 149 secured to the auxiliary frame 23. A weight 150 provided on 80 the end of a lever 151 also secured upon the shaft 148 normally holds the upper roller 146 out of engagement with the central sheet and holds the forward end of lever 151 in engagement with the under face of a cam 152 85 mounted on the outer end of pressure shaft 56 (see Fig. 3). Cam 152 is adapted to depress levers 151, 147 and roller 146 to cause the finished blank to be ejected immediately after the pressers 96 have completed their 90 operation.

Automatic stop mechanism.

Means are provided to prevent operation of the pressers 96 in case any of the central or side sheets should not be fed thereto and said means comprise a lever 155 for each sheet (see Figs. 1, 2 and 4) pivotally mounted upon the lug 65. The forward arm 155^a of each lever is curved about the upper feed roll 49 and normally tends to rotate by its own weight into the path of travel of the sheet from the magazine to the feed rolls as shown in Fig. 1. The other arm of said lever extends rearwardly and is adapted to be engaged at timed intervals by an arm 156, secured to a shaft 157, which is oscillated by means of an arm 158, connected by rod 159 with a link 160 pivotally mounted, as at 161, to gear case 162. Link 160 is provided with a cam roller 163 which rides upon cam 164 and a curved rod 165 connects link 160 with a clutch actuating member 166 also pivotally mounted on gear case 162, which projects into a groove 167 (see Fig. 15) provided in the hub of clutch member 168 secured upon pressure shaft 55. A clutch key 169, slidably mounted within a suitable keyway in clutch member 168, is normally held in engagement with a suitable recess in gear 54 by a spring 170. The clutch key 169 is provided with a cut out portion 169^a having a tapered face 169^b facing in the direction of rotation of the shaft 54, and the end of member 166 is provided with a similar taper 166^a adapted to engage taper 169^b when member 166 is in operative position and thereby force the clutch key out of engagement with the recess of the gear 54, thus stopping the rotation of shaft 55. 130

A spring 171 normally holds member 166 in inoperative position. The rear arm of lever 155 is cut away to provide a shoulder 155^c (see Fig. 2) with which the lower end of 5 arm 156 will engage when a sheet has not been fed.

A second automatic stopping mechanism is also provided to stop the machine in case more than one sheet should be fed to the 10 machine and this mechanism comprises a clutch actuating member 175, pivotally secured to the gear case 162 and connected by link 176 with a rod 177, pivoted to the main frame 20. A screw 178, mounted in a 15 lug 179 of the structure 75 is adapted to engage rod 177 and actuate member 175 against the action of spring 180 when the structure 75 is depressed beyond a certain degree against the springs 76. It will be 20 understood that the hooked end of member 175 engages within groove 167 and is constructed with a tapered face to engage clutch key 169 in a manner similar to that of clutch member 166.

25 *General operation of the machine.*

The operation of the machine is as follows: A supply of central and side sheets being placed in their respective magazines 30 and the power being put in operation, the shafts 49^a, 50, 55, 61 and 62 will be rotated. It will be understood that the machine will be adjusted to the proper width for the blanks by turning screws 29 and 79, by 35 means of handle 80 and chain 81, and also by adjusting the plates 33 and side sheet joggers 98. As the screw 79 is turned, brackets 82 will carry with them the tables 85, which in turn will carry the pressers 96 40 by the co-operative engagement of dovetails 128 and 95^a.

Crank disc 40^a is so arranged that when cam shaft 62 is rotated the feeders 36 will be actuated to pull the lowermost sheet from 45 under its respective pile, the feeder at the beginning of its stroke occupying the position shown in Fig. 5 and the shoes 46 by their frictional contact with the restricted portions 48 shown in Fig. 7 will cause the 50 upper block 41 to move to its upper position, as shown in Fig. 5, thus forcing the teeth 45 into the sheet and pulling the sheet to the feed rolls 49. Due to the inclination 55 of the machine the central sheets will tend to slide by gravity along the rails 110 until they engage the stops 116 while the side sheets will move between the transfer rolls 86, 91 until they engage the stops 117. As the front edge of the sheets pass to the feed 60 rolls 49, the levers 155 are momentarily raised by the arm 156 to permit the passage of the sheets. The central sheet then passes between the rebound preventing rollers and is fed thereby until it engages the stop 116, 65 while in the meantime the side sheets are fed

by the rollers 86, 91. During the feeding of the sheets by the rollers, the pressers 96 are moving downwardly and as the pressers engage the sheets, cams 138 and 152 are arranged to cause the pressers, rails and rebound preventing roller to move downwardly in unison. 70

As the side sheets B pass from the magazines through the feed rolls 49 a narrow strip of glue is applied to the upper faces 75 thereof adjacent the inner edges. It will be noted by referring to Figs. 3 and 12, that the rails 110, in their normal upward position, will hold the central sheet A a short distance above the side sheets. The curvature of cam groove 104 is so arranged that just as the sheets approach the stops 116, 117 the side sheet joggers 98 will be drawn inwardly by the parts 97, 99 and 100 to hold the sheets against the side faces of the 80 rails as clearly shown in Fig. 2. While this action is taking place the pressers 96 are being moved downwardly by the cams 121, and during the initial downward movement of the pressers the central sheet joggers 106 85 will be actuated by the buttons 108 to cause the central sheet to be accurately centered in the machine. Cam 144 is so constructed and positioned that it will engage the curved 90 rod 142 just as the pressers engage the central sheet and the rails 110 will therefore be pulled downwardly until they are flush with the upper face of the bed plates 83 and table 85, the rails and pressers moving in unison 95 during this time but the cam 144 holding 100 the rails in lowered position until the blank is ejected. When the rails have reached this position the under face of the central sheet will be in contact with the glued edges of the side sheets and just at this instant, as the 105 pressers 96 have in the meantime continued their downward movement they will engage the top of the central sheet adjacent its side edges, and force it with considerable pressure against the glued side sheet to securely 110 unite the sheets and form the tripartite blank. During the initial downward movement of the pressers and until they have exerted their pressure against the sheets, there is practically no frictional resistance 115 between the cams 121 and the blocks 127, therefore the blocks 127 will be held to the right of the opening 122 (Fig. 18) until the pressure effect is attained, during which time they will move towards the left thereby 120 providing a rolling frictional effect and greatly reducing the wear upon the cams and pressers which would otherwise occur were it not for this expedient. The mounting of the lower parts of the mechanism upon the 125 box-like structure 75 which is resiliently supported by the heavy springs 76 permits a limited movement of the pressure reacting members which will permit the pressers to be held in contact with the sheets for a suffi- 130

cient time to cause the sheets to be firmly secured, the springs 76 being sufficiently strong to furnish substantial resistance while preventing breakage.

5 As the rails 110 move downwardly the levers 112 carrying the stops 116 and 117 will be moved downwardly by the parts 118 to 120 shown in Figs. 10 and 11 and just as the pressure upon the sheets by the pressers 96 is released, the cam 152 is arranged to cause the lever 151 and associated parts to move the roller 146 downwardly until it engages roller 145, thus causing the finished tripartite blank to be ejected from the machine.

Operation of the automatic stop mechanism.

As the sheets are passing from the magazines to the feed rolls 49 the lever 155 is momentarily raised by the contact of the arm 156 with the lever to permit the passage of the front edge of the sheets. As the arm 156 moves rearwardly and upwardly, from the position shown in Fig. 1, it will reach 25 the reduced outer end of the lever and if a sheet has been fed by the feeding device 36, the forward arm 155^a of the lever will rest upon the top of the sheet and prevent the forward end of the lever from dropping, thereby preventing the rear end of the lever from raising and remaining in contact with the arm 156 when the reduced portion thereof is reached. If a sheet has not been fed, the front end 155^b of lever 155 will drop, to 30 cause the rear end 155^b to remain in contact with the arm 156 during its entire oscillation. The throw of cam 164 is arranged to cause the arm 156 to be oscillated, just as the pressers start their downward movement, 35 and just before the clutch key 169 reaches the clutch actuated member 166. If the lever 155 has followed the arm 156 because of the failure of the feeding device to feed a sheet, the arm 156 will engage the shoulder 155^c to prevent the forward movement of the arm, thereby holding the arm 156 and preventing the return of the roller 163 by the spring 171 and associated parts. It will thus be understood that the clutch actuated 40 member will be held in its operative position until it engages the key 169, thereby causing it to be withdrawn from the recess in gear 54, and thus stopping the rotation of pressure shaft 55 and the operation of the pressers.

If more than one sheet should be fed to the machine there would result an abnormal pressure which would move the structure 75 downwardly against the action of springs 76 an undue amount thus causing screw 178 to move links 176 and 177 and the clutch actuating member 75 to operative position against the action of its spring to cause the stopping of the gear 54 and shaft 55.

65 Various changes in the specific form

shown and described may be made within the scope of the claims without departing from the spirit of the invention.

We claim:

1. In a machine for making paper box blanks, a plurality of sheet holding magazines inclined to the horizontal, a pressing mechanism arranged at a greater inclination to the horizontal than said magazines and means to feed the sheets from said magazines to said pressing mechanism said inclination of said pressing mechanism being sufficient to cause the sheets to slide thereover by gravity after they are withdrawn from said magazines; and stops projecting into the path of movement of said sheets to stop the sliding movement thereof when said sheets reach the proper position to be operated on by said pressing mechanism.

2. In a machine for making paper box blanks, a plurality of sheet holding magazines inclined to the horizontal, a pressing mechanism arranged at a greater inclination to the horizontal than said magazines, means to operate said pressing mechanism, and means operating in timed relationship with said pressing mechanism operating means to feed the sheets from said magazines to said pressing mechanism, said inclination of said pressing mechanism being sufficient to cause the sheets to slide thereover by gravity after they are withdrawn from said magazines; and stops projecting into the path of movement of said sheets to stop the sliding movement thereof when said sheets reach the proper position to be operated on by said pressing mechanism.

3. In a machine for making paper box blanks, a plurality of sheet holding magazines inclined to the horizontal, a pressing mechanism arranged at a greater inclination to the horizontal than said magazines, means to operate said pressing mechanism, means operating in timed relationship with said pressing mechanism operating means to feed the sheets from said magazines to said pressing mechanism, and means to prevent actuation of said pressing mechanism when a failure of said sheet feeding mechanism occurs.

4. In a machine for making paper box blanks, a plurality of sheet holding magazines, a presser mechanism, a pair of bed plates beneath said presser mechanism, means to feed the sheets from said magazines to said bed plates, said bed plates being arranged at a sufficient angle to the horizontal to cause the sheets to slide by gravity over said bed plates and means to stop said sheets and hold them beneath said pressing mechanism.

5. In a machine for making paper box blanks, a plurality of sheet holding magazines, a presser mechanism, a pair of bed plates beneath said presser mechanism, means to feed the sheets from said magazines to said bed plates, said bed plates being arranged at a sufficient angle to the horizontal to cause the sheets to slide by gravity over said bed plates and means to stop said sheets and hold them beneath said pressing mechanism.

- zines to said bed plates, said bed plates being arranged at a sufficient angle to the horizontal to cause the sheets to slide by gravity over said bed plates, means to stop said sheets and hold them beneath said pressing mechanism, and means to prevent rebounding of said sheets when they engage said last-mentioned means.
6. In a machine for making paper box blanks, a presser mechanism, a pair of bed plates beneath said presser mechanism, a pair of rails slidably mounted upon said bed plates, means to force said presser mechanism upon said plates and means to cause 10 said rails to move in timed relationship with said presser mechanism.
7. In a machine for making paper box blanks, sheet feeding mechanism, a presser mechanism, a pair of bed plates arranged beneath said presser mechanism, a pair of rails slidably mounted on said bed plates, said rails and bed plates arranged at an angle to the horizontal to cause the sheets to slide by gravity over said rails, stops to hold said sheets in registry with said presser mechanism, means to force said presser mechanism against said bed plates, means to cause said rails to move in unison with said presser mechanism after said sheets have been engaged thereby and means operated by said rails to move said stops out of engagement with said sheets as the sheets are engaged by the presser mechanism.
8. In a machine for making paper box blanks, a sheet holding magazine, a presser mechanism, means to feed a sheet from said magazine to said presser mechanism and means to glue the sheet as it is fed comprising a glue pot having a delivery spout secured thereto, a glue applying wheel rotatably mounted adjacent to and in contact with the mouth of said delivery spout, said glue pot and spout resting by gravity upon said glue applying wheel whereby accumulation of glue upon the mouth of said spout will be prevented and said glue applying wheel will grind a fluid tight joint upon the mouth of said spout.
9. In a machine for making paper box blanks, a plurality of sheet holding magazines, presser mechanism, a pair of bed plates beneath said presser mechanism, means to feed the sheets from said magazines to said bed plates, said bed plates being arranged at a sufficient angle to the horizontal to cause the sheets to slide by gravity over said bed plates, means to stop said sheets and hold them beneath said pressing mechanism and means to prevent rebounding of said sheets when they engage said last-mentioned means comprising a freely mounted upper roller adapted to rest by gravity upon the sheets as they pass through the machine, a lower roller, means to normally hold said lower roller in contact with the sheet and means to move said lower rollers downwardly in unison with the final downward movement of the pressing mechanism.
10. In a machine for making paper box blanks, sheet feeding mechanism, a presser mechanism, a pair of bed plates arranged beneath said presser mechanism, a pair of rails slidably mounted on said bed plates, said rails and bed plates arranged at an angle to the horizontal to cause the sheets to slide by gravity over said rails, stops to hold said sheets in registry with said presser mechanism, means to force said presser mechanism against said bed plates, means to cause said rails to move in unison with said presser mechanism after said sheets have been engaged thereby and means operated by said rails to move said stops out of engagement with said sheets as the sheets are engaged by the presser mechanism.
11. In a machine for making paper box blanks, a presser mechanism, a pair of bed plates, means to feed a plurality of sheets between presser mechanism and bed plates, means to apply an adhesive to said sheets as they are fed to said presser mechanism, means to cause said presser mechanism to press the glued portion of said sheets into sealing contact to form a composite blank and means to withdraw said blank when the pressing operation is completed, comprising a lower roller and an upper roller, one of said rollers being mounted for movement towards the other, means to normally hold said movable roller away from the other roller, and means to move said movable roller to cause the composite blank to be engaged therebetween after the pressing operation is completed.
12. In a machine for making a composite paper box blank out of a plurality of sheets, a presser mechanism, a pair of bed plates, means to feed the sheets between said presser mechanism and bed plates, and means to hold said sheets beneath the presser mechanism comprising a plurality of stops adjustably mounted on a pair of pivoted levers and means to automatically move said levers to cause all of said stops to be moved in unison to operative and inoperative positions.
13. In a machine for making paper box blanks, a presser mechanism, a pair of bed plates beneath said presser mechanism, central and side sheet magazines, means to feed the sheets from said magazines to said presser mechanism, means to move said presser mechanism to and from said sheets, and means operated by the movement of said presser mechanism to center the central sheets relatively, to said bed plates and presser mechanism.
14. In a machine for making paper box blanks, a presser mechanism, a pair of bed

plates beneath said presser mechanism, central and side sheet magazines, means to feed the sheets from said magazines to said presser mechanism, means to move said presser mechanism to and from said sheets, means operated by the movement of said presser mechanism to center the central sheets relatively to said bed plates and presser mechanism and means operating in timed relationship with said last-mentioned means to move the edge portions of the side sheets under the central sheets and in longitudinal alignment therewith.

15. In a machine for making paper box blanks, a presser mechanism, a pair of bed plates, means to feed a plurality of single sheets to said presser mechanism and bed plates, means to resiliently support said bed plates, means to move said presser mechanism to and from said bed plates, and means to automatically stop said presser mechanism moving means actuated by the supporting means for said bed plates when said bed plates are moved by the pressure of said pressing mechanism beyond a predetermined point.

16. In a machine for making paper box blanks, a presser mechanism comprising a pressure shaft, a presser freely supported by said shaft, a bed plate supported beneath said presser, a rotatable cam mounted on said shaft in engagement with said presser to reciprocate said presser and anti-friction means between said presser and cam.

35. 17. In a machine for making paper box blanks, a presser mechanism comprising a pressure shaft, a presser freely supported by said shaft, a bed plate supported beneath said presser, a rotatable cam mounted on said shaft in engagement with said presser

to reciprocate said presser and anti-friction means between said presser and cam comprising a plate mounted for reciprocation on said presser constructed and arranged to provide a rolling frictional contact with said cam when said presser is forced against said bed plate.

18. In a machine for making paper box blanks, a presser mechanism comprising a pressure shaft, a presser freely supported by said shaft, a bed plate supported beneath said presser, a rotatable cam mounted on said shaft in engagement with said presser to reciprocate said presser and anti-friction means between said presser and cam comprising a plate, anti-friction means between said presser and plate, and resilient means to normally urge said plate and anti-friction means in a direction opposite to the movement of said cam across said plate.

19. In a machine for making paper box blanks, a presser mechanism, means to feed a plurality of sheets to said presser mechanism, means to actuate said presser mechanism and means to automatically stop the operation of said presser mechanism actuating means when said feeding means fails to feed a sheet, comprising a two-armed pivotally mounted lever, one arm of said lever being provided with a stop shoulder, an oscillating arm adapted to engage with said shoulder, a clutch interposed in said presser mechanism actuating means and connections from said oscillating arm to said clutch to cause said clutch to be thrown to inoperative position when said arm engages said shoulder.
